US0D1045623S

(12) **United States Design Patent** (10) Patent No.: **US D1,045,623 S**
(45) Date of Patent: ** Oct. 8, 2024

(54) **DIGITAL CLOCK**

(71) Applicant: **Fujian Youtong Industries Co., Ltd.**,
Fuzhou (CN)

(72) Inventor: **Dongsheng Huang**, Fuzhou (CN)

(73) Assignee: **Fujian Youtong Industries Co., Ltd.**,
Fuzhou (CN)

(**) Term: **15 Years**

(21) Appl. No.: **29/855,362**

(22) Filed: **Oct. 1, 2022**

(51) LOC (14) Cl. **10-01**

(52) U.S. Cl.

USPC **D10/15**; D10/3; D10/24

(58) **Field of Classification Search**

USPC D10/1-2, 15, 24, 3; D14/371, 374, 170,
D14/171; D6/308, 310
CPC G04G 9/00; G04G 13/00; G04G 13/02;
G04G 13/028; G04G 17/08; G04G
17/086
